TAPE MEASURE

Eugene J. Witchger, Saginaw, Mich., assignor to
The Lufkin Rule Company, Saginaw, Mich., a
corporation of Michigan

Application December 11, 1933, Serial No. 701,815

10 Claims. (Cl. 33—138)

This invention relates to measuring tapes in which the casing and the tape are separable and the tape may be employed independently like a measuring rule, to be afterward returned and readily stowed in the casing. It pertains more particularly to push-pull or balanced action tape measures having such separable feature.

An important object of the invention is to provide in a tape measure of the character stated a tape container or casing wherein a less number of parts, in this instance two, shall perform all the functions of the greater number heretofore employed.

An object is to provide a tape measure that combines with the separable feature all of the desirable features of the balanced or push-pull type of apparatus.

Another object is to provide a tape casing that is attractive and unusual in appearance, strong, yet light and capable of being manufactured in large lots at relatively low cost.

A further object is to provide in a tape of the class described a structure that facilitates its entrance into the casing.

Other objects of the invention will appear in the specification, the structural features appertaining thereto being recited in the claims. The accompanying drawing shows the invention in a preferred form.

30 Fig. 1 is a plan view of the tape container with the cover removed;

Fig. 2 is a similar view showing by dotted and solid lines the manner of inserting the separable tape;

35 Fig. 3 is a similar view showing the tape partly stowed and the resilient gapped tape-coiling band partly expanded;

Fig. 4 is an enlarged detail of the fastening that secures the curved guide portion of the tape-coiling band to the peripheral wall of the casing;

40 Fig. 5 is a sectional view taken on line 5—5 of Fig. 4;

Fig. 6 is a fragmentary view of the inner face of the resilient band;

45 Fig. 7 is a sectional view, distorted, showing a preferred casing structure;

Fig. 8 is a similar view showing a modified form of casing, and

50 Fig. 9 is a perspective view of the tape guiding and balancing device.

It may be noted here that metal tapes of the kind adapted for use with my improved container or casing are known in the tape measure art. They are flexible and resilient, preferably non-planar in cross-sectional shape, concavo-

convex for example, and have a normal tendency to spring into straight position, yet are easily coilable.

In the form shown, the casing is shaped so that it can be readily secured by a cord to the user's clothing or to his luggage, reducing the likelihood of getting lost. It consists of upper and lower members and in its peripheral wall 1 is the usual tape opening 2. Preferably, there is an internal boss 3 struck up from the casing. 10 The boss is not absolutely essential to the satisfactory functioning of the tape, but it is advantageous and commercially desirable presenting an annulus 4.

Associated with the casing and the boss is a device that assists in stowing the tape in the casing and also maintains it in a condition of running balance so the tape stays in whatever more or less extended position it may be placed. This device enables the tape to move with ease and 20 certainty while being extended or retracted and while being inserted in the casing or removed therefrom. The tape stowing and controlling device is preferably made of a single piece of 25 spring material, as in Fig. 9. It consists of an outwardly expandable resilient member 5, gapped at 5a. This part 5 preferably encircles the boss 3 so as to define therewith an annular tape-receiving channel 6, which, for purposes of illustration, is shown somewhat exaggerated in thickness. The inner face of band 5 is provided with 30 anti-friction devices, such as spaced projections 7. Integral with the band 5 and preferably comprising an extension thereof is a curved or inclined guide portion 8 that projects over the gap 35 5a and is bent so as to extend outwardly therefrom toward the peripheral wall 1. Where the guide 8 merges into band 5 there is a rather abrupt bend 5b presenting a shoulder. The outer end, 9, of guide 8 is fastened to wall 1 at 10, preferably by detachable means such as is shown in Figs. 4 and 5.

The tape proper may have the usual tape hook at its outer end, and its other end is preferably bent as indicated at 11. Numeral 12, Fig. 3, 45 designates the initial convolution of the tape. It is formed by the conjoint action of members 8 and 5 and, under some circumstances, boss 3 also, when the tape is pushed into the casing.

A tape measure of my invention, when made 50 as above described consists of but three parts, namely, the casing 1, the unitary stowing member, and the tape. It operates as follows:

A suitable tape, indicated in one position by dotted lines and in another position by full-55

lines, Fig. 2, is positioned preparatory to being pushed at random into the casing through tape opening 2 in the peripheral wall 1. Its bent end 11 encounters the curved guide portion 8 and in 5 advancing is deflected inwardly. It passes beneath the abruptly bent member 5b and is suddenly delivered through the gap 5a into the annular channel 6 between boss 3 and band 5. Or else, if the end 11 happens to first encounter 10 the boss 3 the tape end may be deflected by the boss itself against the shoulder 5b and into channel 6.

Guide 8, although resilient enough to yield and accommodate the coil, is made sufficiently stiff to 15 perform the tape-guiding and deflecting function and also to support the band 5 in an approximately concentric position with respect to the case while the latter is being subjected to the frictional and other stresses that are brought 20 upon it by the tape while being coiled or uncoiled.

The shoulder 5b co-operates with guide 8, the band 5 and, in some cases, the boss 3 to constrain the tape to wind compactly and to stay in 25 that condition when completely stowed.

Tape end 11 normally presses outwardly as it makes its initial turn by sliding smoothly around the inner face of member 5. The first convolution takes its shape from guide band 5 which is 30 made sufficiently stiff for that purpose, and becomes the foundation hoop 12 upon which each succeeding convolution lays itself. Member 5 expands outwardly to accommodate each added layer and gap 5a spreads, as shown in Fig. 3. 35 A tape coil thus built up, by adding convolutions from the inside outwardly is termed in the trade an "outside wind" tape.

The projections 7 on the inner face of band 5 facilitate the circular sliding movement of the 40 tape and prevent band 5 from seizing the tape. They lessen the normal tendency of the band to creep with the tape in the direction of rotation of the coil. Undue friction between band and tape would cause a brake-effect, and would prevent 45 smooth balanced push-pull action when the tape and case are used together as a tape measure in the ordinary way. Projections 7 may be of any suitable shape and may be arranged on the band 5 otherwise than is shown in Fig. 6, but it is 50 better if they do not extend clear across the face of the band, because too much tape-breaking effort might be exerted.

Band member 5 may be made of resilient wires 55 instead of the flat strip of ribbon metal here shown, and the equivalent of projections 7 may be produced by suitably crimping the wires.

A suitable fastening means is shown in Figs. 4 and 5 for securing the guide 8 of resilient band 5 to casing 1. Guide 8 is formed with opposed 60 notches 8a, and casing 1 has inwardly offset lugs 1a, 1b, struck up from its peripheral wall to engage the notches when the upper and lower parts of the casing are put together in the manner shown in Figs. 7 and 8.

Fig. 7 shows a preferred form of casing. It can be made economically, using simple dies, yet it is unusual in appearance, being of annular or, as it is termed in the trade, "doughnut" shape. 70 The outer walls of the two halves meet edge to edge and the inner walls fit one into the other, as at 13, and are held together by press fit or otherwise. A large central opening 13a is thus presented.

Fig. 8 shows a modified casing having a central

disk 14 with a hole 14a and having the usual telescoping outer rim 15.

It is now apparent that the unitary members 5, 5b and 8 co-operate, causing the entering end of a separable tape to assume the shape of a hoop which forms the initial inner foundation convolution of the stowed tape coil. Thus is provided in one piece a curved tape-deflecting guide member and a tape-coiling band portion. The portion 5, from shoulder 5b around to gap 5a, 10 is outwardly expansible yet is made sufficiently stiff to avoid creeping while co-operating with the casing element 3 to start the initial hoop 12 and while converting additional portions of tape into additional convolutions. The tape, although 15 separable from the casing, can be instantly applied to it and then works on the push-pull principle with a degree of ease and smoothness that satisfies all requirements.

In my co-pending application, Serial No. 20 657,009, filed February 16, 1933, now Patent No. 1,987,652, January 15, 1935, I illustrated and described a tape measure in which the tape had the characteristic push-pull balanced action, although it was not adapted to be separated from 25 the casing. There the balancing was produced primarily by a coil spring fastened to the inner end of the tape. A secondary tape control element was provided in the form of a weak spring brake band. This brake band was secured at its 30 outer end to the inner wall of the casing at a place adjacent the tape opening. It was made quite weak, being of thin spring material, adapted to creep slightly with the coil so as to distribute over the outer convolution of the tape 35 a frictional pressure sufficient to assist in moderating the efforts of the winding spring; that is to say, the spring band modified the pull exerted by the winding spring when tightly wound. In that structure the balanced action of the tape 40 was the result of the co-operation of the winding spring and the spring band.

The present invention in the embodiment herein shown and described differs in structure and mode of operation from the device of the co-pending application in, among others, the following respects:

In the present device the guide 8 provides an abutment that bends and deflects the advancing free end of a tape and guides it into the channel 50 6 defined by boss 3 and expandable member 5. Member 5 is expandable after the initial convolution 12 has been made into the form of a hoop by the conjoint action of boss 3 and member 5, but the friction of the rotating tape during its 55 continued entering movement is minimized by projections 7 so there is no appreciable tendency of the member 5 to seize upon the tape and creep with it as in the former application.

In the commercial production of tapes the tape 60 band material is not always uniform in spring strength nor in thickness, hence the action of the individual tapes of a lot may not be the same.

In this invention the shoulder 5b and the guide 8 assist in correcting that fault in the manner 65 that will now be described.

Assuming that an extra thick tape, or an extra strong one, is put into the casing and completely coiled, and that the user runs it in and out many times without pulling it completely out. 70 The first outward pull keeps all of the convolutions of the coil in closely packed condition, but the band 5 does not of itself perfectly follow up the reduction in the size of the coil. It does so approximately, but nevertheless it does not hug 75

the reducing coil as tightly as it held the full coil. Then when the tape is again pushed in it again expands band 5. Each time the process is repeated the same thing occurs, so the result is that after such long repeated push-pull handling the coil is found to be considerably enlarged externally and the band 5 is expanded much more than it would have been under conditions of ordinary use. The band may even be forced out by the coil and expand to the full size of the casing, bringing up against the outer wall 1. Without the bend 5b and spring guide 8 the tape would in that event become locked or choked the next time attempt was made to shove the tape in. But parts 5b and 8 avoid that tendency, because, as is shown by dotted lines in Fig. 3, the spring hump formed by bend 5b against wall 1 gives sufficient yield radially outward and at the proper place, to provide the clearance necessary to allow the remainder of the tape to be pushed in. The guide 8 then lies against the casing and so does the band 5, just beyond the bend 5b, giving an arch spring effect that greatly strengthens the inward thrust that is brought to bear on the tape at the place where it is entering the coil. The result is the tape can thereafter be run back and forth an indefinite number of times without gradually becoming blocked or choked. It will take a little more pushing force to push the final end of the tape into position underneath the band 5, but the tape can not lock. There is no winding spring, and the tape is separable from the casing yet has all of the operating advantages of well balanced push-pull tape measures.

In the appended claims I have pointed out the essential elements of my invention, it being understood, however, that the claims are not intended to be limited to the form of the parts illustrated and described further than a limitation to the described form is necessary to distinguish them from the prior art.

Having thus described my invention, what I claim and desire to secure by Letters Patent is:

1. A container for measuring tapes comprising, in combination, a casing having a tape opening in its peripheral wall and an internal boss, an outwardly expansible gapped resilient member that normally encircles the boss and defines therewith an annular channel, projections spaced apart on the inner face of said resilient member, an abrupt bend formed in said member adjacent the gap and presenting a shoulder, an integral guide portion projecting over the gap and outwardly therefrom, and fastening means securing the end of said guide to the peripheral wall of the casing adjacent the tape opening.

2. A container for measuring tapes comprising, in combination, a casing having a tape opening in its peripheral wall, an outwardly expansible gapped resilient band of substantially circular shape, projections spaced apart on the inner face of said band, an abrupt bend formed in said band adjacent the gap and an integral guide portion projecting over the gap and outwardly therefrom, and fastening means securing the outer end of said guide portion to the peripheral wall of the casing adjacent the tape opening.

3. An outwardly expansible gapped resilient member, an abrupt bend therein presenting a shoulder at the edge of the gap, and a guide member extending from the shoulder outwardly and projecting over the gap, said guide member being sufficiently resilient to accommodate the outward expansion of said gapped member and

sufficiently rigid to support the same when subject to the stresses incident to the uses of the tape measure.

4. In a tape measure of the class described including a container having a central hollow boss, an outwardly expansible gapped band that normally encircles the boss and defines therewith an annular channel, an abrupt bend formed in said band adjacent the gap and presenting a shoulder, and a guide portion integral with the band and projecting over the gap and outwardly therefrom, for the purposes set forth.

5. In a tape measure having a casing adapted for receiving and stowing a separable length of spring tape, an outwardly expansible gapped resilient member in band form having an extension thereof constituting a guide member projecting outwardly and over the tape, said guide member being yieldable outwardly in a radial direction to accommodate expansion of the band member, and a spring tape of nonplanar cross-section having an end bent to present a bearing surface for sliding engagement with the inner peripheral faces of said yieldable guide member and said band member.

6. A casing having a tape opening in its peripheral wall, a flexible circular band of spring material within the casing, a portion of said band being bent outwardly from the circle of said band to the peripheral wall of the casing, and presenting at the bend an outwardly yieldable tape-deflecting shoulder, the end of said outwardly bent portion being fastened to the wall of the casing and adjacent the tape opening.

7. A measuring device comprising in combination a casing, an outwardly expansible gapped resilient member secured thereto, projections on the inner curved face of said resilient member, said projections being directed inwardly and spaced apart laterally so as to keep said resilient member from establishing face-to-face contact with and seizing a spring rule of the non-planar normally rod-like type while the rule is being thrust endwise into the casing and coiled within the said resilient member, whereby a condition of balanced smooth sliding push-pull action of the rule is maintained.

8. A measuring device comprising in combination a casing, an internal boss therein and an outwardly expansible gapped resilient member secured thereto, said member and boss presenting between them an annular channel; projections on the inner curved face of said resilient member, said projections being directed inwardly and spaced apart laterally so as to keep said resilient member from establishing face-to-face contact with and seizing a spring rule of concave convex cross section while the rule is being thrust endwise into the casing and coiled within the said resilient member, whereby balanced smooth sliding push-pull actions of the rule are attained.

9. In a tape measuring device of the character described, a casing having a tape opening in its peripheral wall, a resilient tape of normally concavo-convex cross sectional shape completely separable from the casing and adapted to be wound within the casing into an externally wound coil, a band-like annular spring within the casing, having an end connected thereto adjacent the tape opening and substantially surrounding the coiled tape, said band-like spring comprising a plurality of tape-engaging projections integral with the band and circumferentially spaced about the coiled tape, said projec-

tions being adapted to resiliently engage the outer surface of the outer convolution of the tape and prevent the coils of the tape from frictionally engaging the peripheral wall of the casing.

10. A measuring device comprising in combination a casing having a tape-opening, an internal boss located centrally therein and a gapped resilient member secured to the casing, adjacent the tape opening, said member encircling said boss and being expansible outwardly therefrom, said member and boss presenting be-

tween them an annular channel; projections on the inner curved face of said resilient member, said projections being directed inwardly so as to keep said resilient member from establishing face-to-face contact with and seizing a spring rule of concavo-convex cross section while the rule is being thrust endwise into the casing and coiled within the said resilient member, whereby balanced smooth sliding push-pull actions of the rule are attained.
